BURIAL GARMENT

Nathan A. Komer, St. Louis, Mo., assignor to
Lockwoven Hosiery Company, St. Louis, Mo., a
corporation of Missouri

Application July 9, 1934, Serial No. 734,301

4 Claims. (Cl. 2—64)

This invention relates to a certain new and useful improvement in burial garments.

My invention has for its prime object the provision of a quasi-apparel garment for attiring a male corpse when in its burial casket, the so attired body, when exposed to view through a transparent panel of the casket or through the usual door-opening of the casket, then presenting the appearance of a neatly and fully dressed person.

My invention has for a further object the provision of such a quasi-apparel garment which embodies, as substantially a unitary structure, the frontal portions of the customary outer attire of the male person, the garment being economically constructed and manufactured and built up for dressing on a corpse with convenience, facility, and minimum effort.

And with the above and other objects in view, my invention resides in the novel features of form, construction arrangement, and combination of parts presently described and pointed out in the claims.

In the accompanying drawing,—

Figure 1 is a plan view of a burial garment of my invention as dressed on a corpse and the corpse disposed in a coffin;

Figure 2 is a partly opened-out view of the garment as disposed on a body; and

Figure 3 is an opened-out plan view of the garment.

Referring now more in detail and by reference characters to the drawing, which illustrates a preferred embodiment of my invention, the garment comprises a skirt portion A, which may be of any proper or appropriate suit-material, and which in opened-out plan, as shown in Figure 3, is for the most part of oblong-rectangular contour, the skirt A, when on the body, being draped over and around the limbs of the corpse from the waist downwardly a suitable distance, as illustrated in Figures 1 and 2. At its longitudinal center, the skirt A is folded into a pleat, as at 1, which pleat 1 is sewed or stitched from the waist line downwardly, as at 2, in simulation of the usual front and crotch opening of the male trousers.

Stitched or otherwise attached to, and extending upwardly from, the upper-central margin of the skirt portion A, is a false shirt-front B of suitable shirt-material and dimensioned for draping over the upper portion of the torso of the corpse. The shirt-front B is folded and stitched upon itself to include a pair of suitably spaced longitudinal tucks 3, 3, for simulating the

usual button-hole band of a man's shirt, and underlying, and stitched to the side and upper margins of, the shirt-front B, is a piece of reinforcing material 4, while at its upper re-inforced margin, the shirt-front B is stiffened with a split neck-band 5 provided with a suitable centrally located aperture for receiving a collar button 6.

7, 7, designate complementary collar-sections resulting from splitting or severing, as at 8, the usual or customary man's turned-down collar, 10 such sections being suitably mounted upon, and, as at 9, stapled or otherwise permanently attached to, the corresponding sections of the shirt-band 5 and their front tabs being also attached upon the collar-button 6, as shown.

Each collar-section 7 is also provided with a tape or tie-string 10, whereby the collar-sections 7, 7, may be passed individually around the neck of the corpse and then secured thereon by tying the tapes 10 together.

A suitable article of tie-apparel 11 is attached to the collar-sections 7, 7, between the front tabs thereof for overlying the shirt-front B, and overlying the shirt-front B and tie 11, is a vest-front C comprising half-sections 12, 12', in simulation of the sections of a man's vest, the sections 12, 12' being constructed of suiting material preferably matching the goods of the skirt-portion A and provided with the customary buttons 13, where the vest-sections 12, 12' meet at the center of the garment, the stitching of the buttons 13 also serving, it may be said, for securing the vest-sections 12, 12' together.

At its side margins, the vest-front C is stitched or secured, as at 14, to the corresponding side margins of the shirt-front B, and, in the customary manner, extends below the waist-line of the garment for overlapping the upper marginal portion of the trouser-forming skirt-portion A. Attached to and extending laterally from the respective side margins of the vest-front C, is a pair of tabs 15, each provided with a tape or tie-string 16 adapted to be passed around the body and tied together for dressing the garment neatly on the corpse.

In turn, overlying the vest-front C, is a pair of right and left-hand cape-like members or coat-sections D, D', respectively, each, in the present instance, including a sleeve 17, in which, at its outer end, is secured a cuff 18 of linen or other suitable material. The coat-sections D, D' are constructed of appropriate suiting material and each comprises substantially a half-portion of a man's coat, the coat-sections D, D', being equipped with buttons 20 and button-holes 21, respectively.

At its upper rear portion, each coat-section D, D', is sewed or stapled, as at 22, to the corresponding portion of the shirt-section B, the entire assembly of skirt A, shirt B, vest C, and coat-sections D, D', thus forming a unitary garment-structure.

As will thus be readily understood, the garment comprises a body-covering portion A—B—C, having similitude to a pants-shirt-vest ensemble, and 10 a pair of right and left coat-sections D, D' attached in cape-like manner, that is to say, approximately at the shoulders or to the collar of the body-portion A—B—C, the whole being a unitary garment with the coat-sections D, D', swingable widely from the body-portion A—B—C for 15 facilitating the dressing of the garment on the corpse, as will shortly appear.

In use, the garment is stretched out, as shown in Figure 2, and dressed, from the front only, 20 upon the corpse. The coat-sections D, D', being attached merely to and at the respective collar-sections 1, 1, of the garment, may be readily manipulated for inserting the arms of the corpse into the sleeves 17. The garment is then shifted 25 upwardly on the corpse, and the collar-sections 1 placed around the neck thereof, the collar-tapes 10 being employed for securing the collar-sections 1 in the neck-embracing position and the tapes 16 being likewise passed under the body and tied for 30 securing the garment at the waist.

The skirt-portion A is then tucked around the limbs and the side margins of the coat-sections D, D', tucked under the torso, the corpse, when in the casket, then having the appearance of a 35 fully dressed person, as shown in Figure 1.

The garment may be readily and inexpensively constructed, effects a large economy to a family in a distressing situation, and serves most efficiently in fittingly presenting a body to the last remembrance view of family and friends.

It will be understood that changes and modifications in the form, construction, arrangement, and combination of the several parts of the garment may be made and substituted for those herein shown and described without departing from the nature and principle of my invention.

Having thus described my invention, what I claim and desire to secure by Letters Patent is:—

1. A male burial-garment comprising a shirt-front section for overlying merely the upper portion of the torso of the body and having a split neck-band, a skirt-section stitched only at the central portion of its upper margin to the lower margin of the shirt-section, the side marginal portions of the skirt-section being spaced from the shirt-section and freely foldable about the upper limbs of the body, a vest-front section overlying the shirt-section and the seam between the shirt and skirt-sections and at its side margins stitched to the side margins of the shirt-section, a pair of opposed companion coat-sections attached and fixed only to said neck-band for fitting coatwise upon the body and partially over the vest and skirt-sections, and means including

tying-tapes on the vest-section and collar-band for securing the connected sections as a unitary garment on the body.

2. A male burial garment comprising a shirt-front section for overlying merely the upper portion of the torso of the body and having a split neck-band, a reinforcing section flatwise underlying and stitched to the shirt-section, a skirt-section stitched only at the central portion of its upper margin to the lower margin of the shirt-section, the side marginal portions of the skirt-section being spaced from the shirt-section and freely foldable about the upper limbs of the body, vest-front forming sections overlying the shirt-section and the seam between the shirt and skirt-sections, said vest sections being stitched together along the median line, and at their respective outer side margins stitched to the side margins, of the shirt-section, a pair of opposed companion coat-sections attached and fixed only to said neck-band for fitting coat-wise upon the body and partially over the vest and skirt-sections, and means including projecting tabs on the vest-sections and tying-tapes on the tabs and neck-band for securing said connected sections as a unitary garment on the body.

3. A burial-garment comprising, a shirt front-section to overlie the upper portion of the torso, a skirt-section attached only at the central portion of its upper margin to the lower margin of the skirt-section, said skirt-section having the side portions thereof unattached to any portion of the garment and freely extending laterally beyond the shirt-section to be freely and independently draped about and around the lower portion of the torso and the upper portion of the limbs, a vest front-section overlying the shirt-section and the upper marginal portion of the skirt-section and unattached to the skirt-section to leave said skirt section for free and independent draping, and means for securing said connected sections as a unitary garment on the body.

4. A burial-garment comprising, a shirt front-section corresponding substantially to the bosom portion of a shirt to overlie the upper portion of the torso, a skirt-section attached only at the central portion of its upper margin to the lower margin of the shirt-section and having portions extending laterally beyond each side of the shirt-section and unattached to any portion of the garment, said skirt-section being adapted to be freely and independently draped upon the lower portion of the torso and the upper portion of the limbs in simulation of trousers, a vest front-section overlying the shirt-section and connected to the side margins of the shirt front-portion, said vest portion being unattached to the skirt-section and yet extending to cover the line of connection between the shirt-section and the skirt-section, and fastening means associated with said shirt-section and said vest-section to secure such sections in place.

NATHAN A. KOMER.
